UNITED STATES PATENT OFFICE.

MAUDE SIEGEL, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed August 3, 1925. Serial No. 14,301. Term of patent 3½ years.

To all whom it may concern:

Be it known that I, MAUDE SIEGEL, a citizen of the United States, and a resident of the city of New York, borough of Manhattan, in the county and State of New York, have invented a new, original, and ornamental Design for Dress, of which the following is a specification, reference being had to the accompanying drawing, forming part thereof.

The figure is a front view of a dress, showing my new design.

It will be noticed that the pockets have a special contour in that their upper edges

slope downward to a central point leaving a pocket opening of triangular form the background of which is shown as contrasting, and immediately below the point at the lower central upper edge of the pocket a button hole and button are produced these features forming a distinctive characteristic of the design herein presented, as well as the cuffs and rows of buttons at the ends of the sleeves.

I claim:

The ornamental design for a dress, as shown and described.

MAUDE SIEGEL.
